(No Model.)

B. J. NOYES.
SIGNALING APPARATUS.

No. 530,236.

Patented Dec. 4, 1894.

UNITED STATES PATENT OFFICE.

BERNICE J. NOYES, OF BOSTON, MASSACHUSETTS, ASSIGNOR TO GEORGE W. GREGORY, OF SAME PLACE.

SIGNALING APPARATUS.

SPECIFICATION forming part of Letters Patent No. 530,236, dated December 4, 1894.

Application filed February 18, 1890. Serial No. 340,935. (No model.)

To all whom it may concern:

Be it known that I, BERNICE J. NOYES, of Boston, county of Suffolk, State of Massachusetts, have invented an Improvement in Signaling Apparatus, of which the following description, in connection with the accompanying drawings, is a specification, like letters on the drawings representing like parts.

United States Patent No. 359,688, granted to me March 22, 1887, shows and describes a signaling apparatus especially adapted for police signaling purposes wherein multiple signal transmitters are arranged in boxes at different points along the streets, and connected by an electric circuit with a central or receiving station, and a register is employed at said central or receiving station which receives all the signals transmitted, and a bell or other indicator is also located at the central or receiving station which responds on the reception of some of the signals only. As a means for effecting such differentiation, the impulses transmitted vary in length of duration, that is, some signals comprise a series of short changes and others comprise a long change followed or preceded by a series of short changes. Many of the special signals indicate a wagon call, and as the wagon is oftentimes kept some little distance from the central or receiving station, another signal transmitting apparatus is employed, connecting the central or receiving station with the wagon house, and the attendant, after receiving a wagon signal, repeats it to the wagon house. In addition to the expense of constructing such a wagon call system, and keeping it in order, I find that the attendant unless extremely careful, is liable to make mistakes in reporting the call, and hence sends the wagon to the wrong box.

This invention has for its object to construct and arrange a signaling apparatus, whereby all the signals transmitted from the signal boxes are received at the central or receiving station and all the wagon calls are received at the wagon house direct, while a bell or other indicating signal is located at the central or receiving station to respond to the wagon calls.

Also in accordance with this invention, tele-

phones are connected in the signaling circuit from the street boxes to the central station and the ordinary magneto-call employed.

This invention also comprehends the employment of particular means for carrying out the several results.

Figure 1 shows in diagram a signaling circuit and instruments therein constructed and arranged to carry out the results embodying this invention; Fig. 2, a front view of a signal box which may be employed in carrying out this invention.

Referring to Fig. 2, the signal box comprises a shell or case *a*, having a face plate *b*, and door *c*. A multiple signal transmitter is contained in the box *a*, having a pointer *p*, which moves over a dial on the face plate, said transmitter being of any well known construction, such for instance as shown and described in United States Patent No. 320,032, dated June 16, 1885. The signal box also contains telephonic instruments such as a transmitter *t*, receiver *t'*, and a magneto-call *t''*.

In the diagram, Fig. 1, the signal boxes are represented at *S*. The dotted line *d*, represents the wagon house, or auxiliary station, and dotted line *e*, the central or receiving station. The main signaling circuit *f*, leads into both the central station, and wagon house or auxiliary station. A register *R* is located at the central station, which is herein represented as included in a local circuit *n* containing a battery *n'*, said local circuit being controlled by the armature bar *n''*, of a relay *n''*, which is included in the main circuit *f*, containing the main battery *f'*. A ground tap or branch *m*, leads from the signaling circuit, it including a magneto-bell *m'*, telephone transmitter *m''*, receiver *m'''*, and condenser *m''''*, all connected in any usual or desirable manner. All the telephone calls are received on the magneto-bell *m'*. All the regular signals are received on the relay *n''*, and hence all will be duly recorded on the register *R*.

At the wagon house or auxiliary station *d* a relay *o* is included in the circuit *f* the armature *o'* of which when retracted closes a local circuit *o''*, containing a local battery *o'''*, a recorder *o''''*, and a bell or other indicator *o'''''*.

As it is desired that the relay *o*, shall be ef-

fected only on the occurrence of the wagon calls, some means of distinction must be employed, and for simplicity, I have herein employed as a distinguishing impulse one of long duration in contradistinction to those of short duration, and the armature-bar has, or is secured to, a toothed sector o^6 with which operates a pallet o^7 . Upon the occurrence of an impulse of long duration, the armature o' receding with a slow movement owing to the action of the retarding device shown, will strike a contact o^8 . Owing to the construction of the retarding device, the armature o' will also be attracted slowly, and hence when against the contact o^8 , will vibrate back and forth opening and closing the local circuit o^2 , so that as a series of short impulses follow the long or distinguishing impulse, the recorder o^4 and bell o^5 will respond. One of the instruments o^4 or o^5 , may be omitted.

The local circuit o^2 extends from the wagon house or auxiliary station d to the central station e , and at the last-named station, a bell u or, it may be, a visual indicator or other receiving instrument is included in said local circuit so that as the recorder o^4 or bell o^5 operate, the bell or indicator u will respond and indicate at the central station the wagon signals. This local circuit connecting the wagon house or auxiliary station with the central station is an important feature, because it is absolutely necessary that the attendant in charge at the central station should know when the wagon calls come in, to determine when and where the wagon is called, and by arranging the bell in the same circuit with the receiving apparatus at the wagon station, and thereby controlled by the same circuit changing device which controls the instruments at said wagon house it is safe to conclude that when the bell at said central station is operated, the receiving instruments at the wagon house, are also operated; and furthermore as the receiving instruments at the wagon house are operated directly from the boxes, there is no liability of mistakes on the part of the attendant in charge, who now repeats them.

I claim—

- 50 1. In a police signal system, signal boxes, each containing a multiple signal transmitting apparatus, constructed and arranged to transmit different signals and to produce distinguishing impulses with some and not with others; a central station; a receiving apparatus thereat in circuit with and to receive all the signals transmitted by said signal transmitting apparatus; combined with a distant auxiliary station; a circuit changing device thereat controlled by said circuit and operated by said distinguishing impulses; a tell-tale local circuit controlled by said circuit changing device and leading from the said auxiliary to said distant central station; and an indicating device in said local circuit at said central station to indicate at the latter the reception of a signal at the distant

former station; and a signal receiving instrument at said auxiliary station and responsive to signals transmitted by said signal transmitting apparatus, substantially as described. 70

2. In a police signal system, signal boxes, each containing a multiple signal transmitting apparatus, constructed and arranged to transmit different signals and to produce distinguishing impulses with some and not with others; a central station; a signal receiving apparatus thereat in circuit with and to receive the signals transmitted by said signal transmitting apparatus; combined with a distant auxiliary station; a circuit changing device thereat controlled by said electric circuit and set in operation by said distinguishing impulses, and thereafter operated by and responsive to the regular impulses of signals transmitted; a tell-tale local circuit controlled by said circuit changing device and leading from said auxiliary to said distant central station; a signal receiving instrument at said auxiliary station and controlled by and responsive to changes in the condition of said local circuit; and a tap bell also in said local circuit but located at the said central station to tap the box number at the latter station simultaneously with its reception at the distant auxiliary station, to indicate at the former proper reception of the signal at the latter, substantially as described. 80 90 95

3. In a police signal apparatus, signal boxes, each containing a multiple signal transmitting apparatus, constructed and arranged to transmit different signals and to produce distinguishing impulses with some and not with others; a central station; a receiving apparatus thereat; a relay controlling the circuit of the said receiving apparatus and in circuit with said transmitting apparatus, combined with a distant auxiliary station, a circuit changing device thereat also in said circuit and responsive first to said distinguishing impulses only, and thereafter to the regular impulses of signals transmitted, a local circuit controlled by said circuit changing apparatus and containing a signal receiving instrument located at the auxiliary station; and an audible alarm device located at the distant central station, whereby only special signals distinguished by said distinguishing impulses are received at said auxiliary station and their reception made known by said audible alarm at the distant central station, substantially as described. 100 105 110 115

4. In a signaling apparatus, a main signaling circuit connecting street boxes, a central station, and a wagon house, a receiving instrument at the receiving station for receiving all signals, combined with a receiving relay at the wagon house, a retarded armature therefor, a local circuit controlled by said retarded armature, and two receiving instruments in said local circuit, one at the wagon house, and the other at the central station, substantially as described. 125 130

5. In a signaling apparatus, a main signal-

ing circuit connecting street boxes, a central station, and a wagon house, and a receiving instrument at the central station for receiving all signals, combined with a receiving relay at the wagon house, an armature therefor, and a retarding device for the armature operative to retard its progress in both directions, a local circuit controlled by said armature, and two receiving instruments in said local circuit, one at the wagon house,

and one at the central station, substantially as described.

In testimony whereof I have signed my name to this specification in the presence of two subscribing witnesses.
